UNITED STATES PATENT OFFICE

2,515,585

EDGE GUIDE FOR SEWING MACHINES

Raffele Bisignano, Elmhurst, N. Y., assignor of
one-half to Florence E. Bisignano, Elmhurst,
N. Y.

Application October 21, 1948, Serial No. 55,694

1 Claim. (Cl. 112—153)

1

This invention relates to new and useful improvements in attachments for use in manufacturing an article of footwear, and, more particularly, the aim is to provide a novel and valuable device adapted to be attached to a sewing machine and then for employment in easily and quickly applying a stitch with the line of such stitch always at a uniform distance from a bounding edge of a sole member of the shoe.

The new device, which is exceedingly simple, which nevertheless is readily securable in place on a sewing machine already in use, and which, moreover, is readily adjustable to vary said distance precisely as desired for gauging the distance between the upper and the stitch while the belt is being applied. A feature of the invention is the stark simplicity of the attachment, its efficiency in action, its low cost of fabrication, and its easy adjustability.

The new attachment comprises merely a gauging tool constituted by a free spinning roller which at the same time acts to effectuate the attachment as a friction reducing and work expediting instrumentality; a small bar like member shaped at one end to present a laterally narrowed and upstanding overhang portion for overlying the roller and from which the roller is revolvably suspended; and screw and slot means, the slot whereof may be carried by said member, whereby the attachment may be substantially instantaneously adjustably secured on a sewing machine so as to direct said roller predeterminedly toward the field of reciprocation of the needle.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a top plan view of a now favored embodiment of the new attachment, drawn to almost exactly twice actual scale.

Fig. 2 shows the same in side elevation, partially in section at the roller and the roller supporting overhang portion.

Fig. 3 is a bottom plan view thereof.

Fig. 4 is a transverse vertical section, taken on the line 4—4 of Fig. 2.

Fig. 5 illustrates the attachment in use as a speed roller gauge in applying a stitch around a sock lining or insole footwear member.

Referring to the drawings more in detail, the

2

aforesaid roller, a tiny cylindrical one which as herein shown has a length equal to about half its diameter, is designated 10. The aforesaid small bar like member, of somewhat greater length than width and of less thickness than width, is shown at 11. This member is of rectangular cross section along the major part of its length, below called its main tang or arm portion 13; and said member at one end is shaped to present a projecting overhang portion 12. Said portion 12 is narrowed laterally of said arm portion 13, is extended centrally thereof, and is upstanding above the top flat or general plane of the arm portion 13, where the member 11 is provided with an elongate slot 14; the underside of the said overhang portion 12 lying in the same plane with said flat.

In a direction away from the roller 10, the overhang portion 12 is joined to the slot-carrying arm portion 13 of the member 11 by an outwardly, rearwardly and downwardly curved rib 15, attended at the top of the member 12 by a laterally concavely arched longitudinally curved recess 16 which gradually increases in width until it reaches the bottom of the member 11 opposite the forward end of a bottom rib 17. Said bottom rib 17, as shown best in Fig. 4, is of the same width as the overhang portion 12, and is attended, at the bottom of the member 11, and on the side of the latter opposite to the side thereof at which the recess 16 is located, by a laterally concavely arched and outwardly, rearwardly, upwardly extending longitudinally curved recess 18. Said recesses 16 and 18 at their ends remote from the roller 10 desirably merge imperceptibly with the member 11.

These formations on the small member 11 allow the same, as is preferable, to be readily and inexpensively formed of a single integral structure, and provide at the recesses 16 and 18 well and/or upper fulling and accommodating compartments facilitative of speed and convenient action of the attachment during the laying down of a line of stitching.

The overhang portion 12 is drilled vertically to provide an aperture 19, countersunk at its top as shown in Fig. 2, and a cylindrical stud 20 having at its bottom an integral preferably wafer-thin circular disk head 21 is upset in said countersink as at 22, so as to mount the roller 10 with a free rolling fit on the stud 20, and with the lower face of the head 21 flush with the plane of the bottom of the arm portion 13 of the member 11.

Referring to Fig. 5, a well-known type of stand and sewing machine is here shown, including a

vertically reciprocating needle 23, a work guiding boot 24, and a floor plate 25.

The means for adjustably securing the new attachment in place comprises the aforesaid screw and slot means, of which the slot element is the slot 14 of the member 11, and of which the screw element is a set-screw 26 spirally tightenable in a hole (not shown) drilled and tapped through the floor plate 25.

Thus, with the new attachment arranged as shown in Fig. 5, and with the set-screw 26 tightened to direct and hold the roller 10 exactly as desired relative to the boot 24, a footwear article, such as that indicated at 27, may be rapidly and easily advanced relative to the field of operation of the needle 23, and stitched as indicated at 28, with such line of stitching held at a predetermined uniform spacing from the bounding edge of the shoe component 29 all around the same or all along that portion thereof which is to be thus stitched.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new and desire to secure by United States Letters Patent is:

In an attachment for the purpose stated having an arm for adjustable attachment to the floor plate of a sewing machine with one end closely adjacent the reciprocating needle of the sewing machine, the arm being formed at the said one end with an overhanging portion having its bottom face spaced above the bottom face of the arm, an apertured roller positioned beneath the bottom face of said overhanging portion, a stud 10 having its top end secured to said overhanging portion said roller being rotatively engaged on said stud, and a wafer-thin circular head formed on the bottom end of said stud and upon which the bottom face of said roller surrounding its aperture rests, said head having its bottom face flush with the bottom face of the arm to rest on the floor plate for reinforcing the overhanging portion of the arm while at the same time supporting said roller raised slightly off the floor plate 20 out of frictional contact therewith.

RAFFELE BISIGNANO.
